UNITED STATES PATENT OFFICE.

JAMES LYALL, OF NEW YORK, N. Y.

IMPROVEMENT IN LOOMS.

Specification forming part of Letters Patent No. 80,982, dated August 11, 1868.

To all whom it may concern:

Be it known that I, JAMES LYALL, of the city and State of New York, have invented and made a new and useful Improvement in Looms for Weaving; and I do hereby declare the following to be a full, clear, and exact description of the said invention, reference being had to the annexed drawings, making part of this specification, wherein—

Figure 1 is a vertical longitudinal section of the loom fitted with my improvements. Fig. 2 is an elevation of the lay and parts connected therewith. Fig. 3 is an elevation of the shuttle and shuttle-driver in larger size. Fig. 4 is a section of the same and of the lay and reed. Fig. 5 is an end view, and Fig. 6 is a plan of the shuttle driver detached, and Fig. 7 is a plan of the lever and its connections that are employed to give motion to the shuttle-driver.

Similar marks of reference denote the same parts.

My invention relates to a loom for weaving, in which the shuttle is operated upon and moved continuously during its entire passage across the fabric being woven. Efforts have before been made to attain this object. My devices are improvements that render this operation practically successful. My improvements relate to the manner of constructing the shuttle and the shuttle-driver, and also to the manner of supporting them in the lay and giving motion to the shuttle-driver.

In the drawing, *a a* are the side frames of the loom, connected together by suitable braces. *b* is the breast-beam, over which the woven cloth passes. *c* is the yarn-beam; *d*, the whip-roller, over which the yarn passes. *e* is the cloth-roller. To the yarn-beam *c* a suitable let-off motion is applied, and to the cloth-beam *e* a take-up motion is fitted. The heddles *f f* are made as usual, and operated by the foot-levers *g g* and cams *h h*, on the shaft *h'*, driven by competent power. These cams *h* are shaped so as to change the shed at the proper time, and to hold the shed open during the passage of the shuttle, and the parts thus far described being all well known, both in construction and operation, do not require further description, and I remark that the heddles may be set and operated to weave either plain, twilled, or figured goods.

My improvements apply to the lay, the shuttle-race, shuttle-driver, and the operative parts next described.

The lay is mounted upon the fulcrum *i*, the swords *k* extending up and connecting with the raceway *l*, that extends from end to end of the lay, and receives the shuttle-driver, hereafter described. The portions of the lay that project beyond the sides of the fabric that is to be woven are extended upward and connected with the top or shuttle rail *w* of the lay. This raceway *l* and shuttle-rail *w* can be made of either wood or metal. I, however, prefer that they be made of wood, and the bottom and edges of the raceway and the lower surface of the shuttle-rail should be made of layers of hard wood, so as not to be worn by the friction to which they are subjected.

In Fig. 4 the dotted lines denote the position of the warps when the shed is open, and from this it will be seen that sufficient space is left between the raceway *l* and the shuttle-rail *w* for the opening of the warps by the heddles, the upper shed, however, coming into contact, or nearly so, with the under side of the rail *w*. The front portion of the shuttle-rail *w*, against which the shuttle runs, is to be made adjustable nearer to, or farther from, the raceway *l*, so as to provide for wear in the parts, or for variations in the shuttle, the driver, or the thickness of warps in the loom.

In order to introduce the reeds *n*, I groove the respective parts *l w*, for receiving the top and bottom reed-bars. *n²* and *n¹* are clamps for holding these bars firmly to their place. (See Fig. 4.) By this way of securing the reed-bars the parts *l* and *w* are tied together and prevented from spreading under the action of the shuttle and shuttle-driver in passing across the fabric. If, however, this connection by the reeds is not sufficient in very wide looms, a plate of thin-sheet metal may be introduced between the warps some little way behind one of the reed-plates and connected at its ends with the rail *w* and raceway *l*, or several of these plates may be employed at suitable distances apart. The shuttle driver *o* is formed as a frame fitted to travel in the raceway *l*, and provided with rollers *2 2*, that travel upon the bottom of said raceway, and with rollers *3 3* that travel in contact with the under side

of the warps and give motion to the shuttle. These rollers 2 and 3 are arranged in pairs near the ends of the shuttle-driver, and their surfaces are in contact, so that the rotation of the rollers 2, by contact with the bottom of the raceway, is communicated to the rollers 3; therefore the surfaces of the rollers 3, in contact with the under side of the warps, do not cause any friction or wear upon them, because the surfaces of the rollers are traveling at the same speed as the roller itself is moving bodily. In consequence of this peculiarity I am enabled to slightly raise the warps as the rollers pass under them without disturbing the warps horizontally, and thus apply a constant pushing action to the rollers 4 of the shuttle that is on the other side of the warps, to cause it to roll progressively across the fabric to be woven, instead of having to be thrown suddenly, as heretofore usual.

The shuttle-driver may be provided with a spring cro s-piece, traveling in grooves in the sides of the raceway to keep the rollers in contact with the bottom of the raceway and insure their turning. The shuttle itself is formed of a body, *p*, having a cavity in one side for the reception of the bobbin or spool *q*, from which the weft-thread is led through a delivery-eye, and in the lower part of the shuttle are the rollers 4 4, one near each end, and the rollers 5 5 are introduced in the upper part of the shuttle, near the ends, and run against the lower edge of the shuttle-rail *w*, the upper shed of warps intervening.

It will be seen, on reference to Figs. 3 and 4, that the rollers 5 stand at an inclination, so that their axles are parallel to the inclined under surface of the rail *w*, and that by this means I effect two important objects: first, the warps are raised into contact with the under side of *w*, and remain resting against the inclined surface, while the rollers 5 travel on the other side of said warps, and, hence the warps are not disturbed or injured in the least, and, in fact, are only consolidated by the pressure; and, second, the back of the shuttle is wider than the front, and the distance between the back edges of the rollers 4 5 is greater than that between the front edges, hence the shuttle cannot jump out of place, either while in the cloth or in the lay beyond the edges of the cloth, and the reeds and back of the lay prevent the shuttle moving back away from its proper position.

The width between the rail *w* and raceway *l*, outside the edges of the fabric, is to be slightly less, to compensate for the absence of the warps at these points, and prevents the shuttle and driver being too loose when out of the cloth.

It will now be seen that the shuttle travels very near the point at which the cloth is made, and hence the lay has but little movement, and the heddles do not require to be opened as wide as usual, and that the shuttle can be propelled continuously across any width of

fabric if the shuttle-driver is given the requisite motion.

The means for moving the shuttle-driver may vary according to the character of loom, the width of fabric, and the speed required. It is important that the speed of said driver be gradually lessened toward the ends of its reciprocation and gradually started or accelerated so as to avoid any concession of the parts or sudden strain on the weft-thread.

I have represented a means for effecting these objects, which will be next described.

Upon the main shaft *h* is a cam, *r*, that is formed as a trough, receiving a roller, *s*, on the lever *t*, or as a rib between two rollers on said lever. I have shown the former. The bottom of this groove is equidistant at all points from the center of the shaft, and at the parts 6 and 7 it is cylindrical and in planes at right angles to said shaft, but at the parts 8 and 9 said groove is diagonal, and the respective portions are united by curves at 10, of more or less radius. (See Fig. 2.)

By this form of cam the lever *t* is swung first one way and then the other, a pause occurring in its movement when the roller is in the part 6 or 7, and the loom is so timed that at these periods the lay is moved to beat up the filling or weft. The curves at 10 stop and start the lever *t* gradually, and the diagonal positions of the groove at 8 and 9 are such that the lever *t* will be moved more or less rapidly in proportion to the arc through which the cam revolves in producing that motion, and as the shuttle is moved by a connection from the end of this lever *t* to the shuttle-driver, the travel of the shuttle, its gradual stopping and starting, are regulated by the shape of the cam *r*.

From the ends of the shuttle-driver *o* bands, cords, or catguts *u* pass each way over the pulleys *u* down to the pulleys 11 11, that are on the swords of the lay at a level corresponding to that of the moving end of the lever *t*, and the said belts are connected at opposite sides of this end of said lever.

If the lever can be moved with facility the amount required for the travel of the shuttle, the said connection of the belts may be direct, but generally the motion will have to be multiplied. This is effected by two, four, or more moving pulleys, *v*, upon the end of the lever *t*, around which the belts pass from the pulleys 11, and are attached at their ends to the frame *a* of the machine, or to the lever, so that twice or more times the motion can be given to the shuttle-driver than is given to the end of the lever, the amount of length of belt drawn in or given off by each movement of the lever depending on the number of moving pulleys and the times the rope is returned around them.

Any suitable means may be employed to give motion to the belts that connect with the shuttle-driver, such as a wheel that is rotated or revolved by the action of a pinion and turns first one way and then the other, or a recipro-

eating slide or rack may take the place of the lever, or a series of wheels and pulleys belted together so as to multiply the speed may be employed, but I find the devices shown to operate satisfactorily.

The lay may be moved by any desired means. I, however, prefer to employ the cams w , (see Fig. 1,) on the shaft h' , that are shaped as arcs of circles at the two points 13 and 14, so as to allow the lay to remain stationary while the shuttle is in motion, the cam-shapes 15 and 16 giving the beat-up by acting against the rollers 17 on the lay, and the lay may be thrown back by a spring, but I prefer that the cams w' be formed with flanges that run between pairs of rollers, which are connected with the lay, thereby insuring a positive movement to all parts of the loom. It will be preferable to have one roller of each pair mounted on a slide that has a limited motion, and a spring to force the rollers toward each other, and thereby prevent the parts wearing loose or becoming noisy.

When it is desired to weave with different-colored weft-threads, changeable shuttle-holders may be provided to act at the end of the lay.

The advantages of this loom over others may be briefly enumerated, thus: The weft is not subject to sudden pulls in starting, hence may be of the most delicate texture even in the widest fabrics, because the shuttle is started gradually instead of suddenly, as heretofore. The reed moves but a little distance, and does not wear the warps. The width of the fabric may be extended indefinitely. The loom runs with less power, and much more quietly, than heretofore, hence there is less wear on the machinery, and the building containing the same is not injured. The shuttle is held and entirely controlled by positive-acting mechanism at all times, hence it cannot stop in the cloth and injure the fabric, as is now frequently the case, neither can the shuttle jump out of the loom, as it often does in the ordinary looms, at the risk of injury to itself or the other parts of the machine, or of the attendants, and, in case of the loom being stopped, each part is in place for starting again. It will therefore be seen that every part and motion in this loom is by a direct and continuous connection with the motive-power, and there are no parts that are operated upon by concussion and alternately held and released, as in the ordinary loom; therefore the risk of injury to any portion of the fabric or to the machinery is almost entirely removed. Several pieces of narrow-width goods may be woven in a loom adapted to wide widths by leaving sufficient space between the respective pieces for the shuttle, and introducing as many shuttle-drivers o upon the belt u as there are pieces of fabric, and providing the same number of shuttles, and lessening the movement

given to the band u , so that the shuttles will be carried simultaneously through the respective fabrics, first one way and then the other, thus making a selvage on each piece of goods. By this means a wide loom can be made use of instead of remaining idle when there is not a demand for the particular width of goods.

What I claim, and desire to secure by Letters Patent, is—

1. A vibrating lay and a reciprocating shuttle (adapted to passing either end first between the warps) in combination with a carrier provided with actuating-rollers that are moved across the vibrating lay on the other side of the warps, and to which an independent rotary motion is communicated in the same direction that the rollers would be rotated by contact with the warps, substantially as and for the purposes specified.

2. In combination with the reciprocating shuttle and lay, a shuttle-driver provided with rollers, substantially as described, so that the rollers that come in contact with the warps are rotated by contact with the rollers that support the shuttle-driver, substantially as set forth.

3. The reed and lay having a raceway, l , and a shuttle-rail, w , substantially as set forth, in combination with the reciprocating shuttle-driver, and the shuttle that is actuated by said driver, substantially as set forth.

4. A vibrating lay in combination with a reciprocating shuttle and a shuttle-driver that operates upon the shuttle during its entire reciprocation, the warps intervening, substantially as set forth.

5. Two or more moving pulleys combined with the said shuttle-driver, and connections to the same, substantially as set forth, so as to multiply the movement in operating on the shuttle-driver, as specified.

6. The cams operating, substantially as specified, to stop and start the shuttle gradually and operate while the lay is stationary, in combination with the cams for operating the lay while the shuttle is stationary, substantially as set forth.

7. The cam w' , formed of a flange, in combination with the two rollers that are connected with the lay, one of which is yielding, and between which said flange moves, substantially as set forth.

8. The shuttle-driver, substantially as specified, in combination with cords or their equivalents that pass off on opposite sides and are connected to the actuating mechanism at or near the line of the axis or fulcrum of the lay, substantially as specified.

Dated April 24, A. D. 1868.

JAMES LYALL.
